UNITED STATES PATENT OFFICE.

OLIVER D. WOODRUFF, OF SOUTHBURG, CONNECTICUT.

MEAT-CUTTER.

SPECIFICATION forming part of Letters Patent No. 443,590, dated December 30, 1890.

Application filed June 21, 1890. Serial No. 356,291. (No model.)

To all whom it may concern:

Be it known that I, OLIVER D. WOODRUFF, a citizen of the United States, residing at Southington, in the county of Hartford and State of Connecticut, have invented certain new and useful Improvements in Meat-Cutters, of which the following is a specification.

My invention relates to improvements in meat-cutters; and the objects of my improvements are simplicity of construction and general convenience and efficiency in operation.

In the accompanying drawings, Figure 1 is a front elevation of my machine, the end of the crank being broken off and removed.

Fig. 2 is a side elevation of the crank end of the same, the crank being removed. Fig. 3 is a detached horizontal section on line $x-x$ of Fig. 2, the central member being shown in plan view. Fig. 4 is a horizontal section of the case on line $y-y$ of Fig. 1, the other parts being shown in plan view. Fig. 5 is a vertical section of the combined forcer and cutter on the line $z-z$ of Fig. 4. Fig. 6 is a developed plan or diagram showing the prominent surfaces of said forcer and cutter. Fig. 7 is a vertical section of the case on line $w-w$ of Fig. 2, and Fig. 8 is a developed plan or diagram showing the prominent inner surfaces of said case.

In general the case A is of a conical form, having the driving-crank B and hopper C at the large end. I have, however, illustrated a portion of the case immediately under the hopper as cylindrical, and this is the preferred form; but, if desired, the taper shown at the delivery end might continue the whole length of the case. On the interior of the case at the top and immediately beyond the hopper is a circumferential rib or cutter 9, which extends around for about half the circle of the case, and a little farther toward the small or delivery end of the case is a second circumferential shoulder or cutter 10, which extends around the entire circle of the case, excepting as it is intercepted by feeding-ribs hereinafter described. Upon the front side of the case the interior is provided with a longitudinal shoulder or cutter 11, the same, however, being somewhat inclined with reference to the axis of the case to present it at a shearing angle to the revolving longitudinal cutters hereinafter described. The interior

surface for the upper half of the case above the cutter 11 is smooth and true and formed with a series of cutters by means of perforations 12, forming a compound cutter of the well-known perforated-plate class.

Underneath the hopper and over such portions of the interior of the case as are not occupied by the cutters already described the case is provided with inclined feeding-ribs 13, their prominent surfaces being flush with the cutters before described and merging into the same at their junctions, also stopping a little short of the cutter 11 or merging into it, if desired.

The large end of the case is provided with a band or rim 14, the inner surface of which is provided with a smooth cylindrical bore. The case is provided on the outside of this rim with horizontally-projecting lugs or studs 15 for securing the cap or end plate. The case is also provided with a suitable standard or support D of any ordinary construction.

The cap or end plate E is provided with a central outwardly-projecting hub 17, which is bored to form bearings for the crank-shaft 18, and upon its inside with a circular hub 16, which fits the bore of the rim 14, as shown most clearly in Fig. 4. Said cap E is also provided with hooked and inclined lugs 19, that engage the lugs or projections 15 and draw the cap into the case as the cap is turned to force said lugs into engagement with each other. I provide the upper edge of said cap with a series of fine notches or serrations 20 for being engaged by the holding-dog 21 for holding the cap in position when adjusted. This dog is secured to the case upon an eccentric or crank-pin 22, the same having a suitable handle by which it may be revolved and by turning which the point of the dog 21 may be withdrawn from the serrations 20 or forced firmly against the same for locking the cap in place.

The combined forcer and cutter F has its periphery or prominent surfaces made to correspond to and fit the prominent inner faces of the case. The flange 23 at the end is made to fit the bore of the rim 14. From this flange an inclined forcing-rib or screw 24 extends a little more than one revolution, passing the longitudinal cutter 25 and stopping a little

short of the longitudinal cutter 26. The next forcing-rib 27 is a little shorter and extends beyond the longitudinal knife 32 and stops a little short of the knife 25. The next forcing-rib 28 is a little shorter than rib 27 and extends beyond the longitudinal knife 33 and nearly to the longitudinal knife 32. The next forcing-rib 29 extends beyond the knife 26 and nearly to the knife 33.

On the back side of the several knives there is a short forcing-rib 30, substantially in alignment with and forming an extension of the several ribs which stop immediately in front of said knives. By stopping the forcing-ribs a little short of the longitudinal knives a longitudinal space is formed immediately in front of each of said knives.

The outer end of the combined forcer and cutter has a plain conical surface 31 of a size to fit and fill the case. This construction of the combined forcer and cutter furnishes one forcing-rib, which extends across the whole distance under the hopper, but leaves a large open space at other points, so as to freely receive the meat. As the meat leaves the hopper it is forced into smaller grooves or spaces between the forcing-ribs and delivered to the respective cutters, there being one cutter for each of the forcing-ribs leading to a space in front of the several cutters. The core of the combined forcer and cutter gradually thickens relatively to the periphery, so that the spaces between the forcing-ribs are of less depth as they reach the small end, where they are quite shallow. The forcing-ribs on the combined forcer and cutter are so inclined as to cross the feeding-ribs of the case at an obtuse angle, while they cross the circumferential cutters at an acute angle, so that the spiral ribs of the combined forcer and cutter force in connection with the feeding-ribs of the case and cut in connection with the circumferential ribs of the case. These forcing-ribs also serve as cutters in connection with the perforations of the case, while the longitudinal cutters 25, 26, 32, and 33 also cut in connection with said perforations and at the same time cross the cutter 11 of the case at an obtuse angle and give a shearing cut thereon. The meat is easily and quickly fed, and is partially cut on its way to the perforations, so as to more readily enter therein, thereby facilitating the final cutting at said perforations through which the meat is delivered from the machine.

The entire prominent surfaces of the combined forcer and cutter have a bearing on all the prominent inner surfaces of the case, so as to give an extended bearing and prevent rapid wearing away of the parts. The taper-

ing portions of the combined forcer and cutter and interior of the case are kept in contact by means of the cap E, which may be tightened up and held in place by the dog 21. By loosening the dog 21 the entire combined cutter and forcer, with the cap thereon, may be removed from the case. When thus removed, all the parts are readily accessible and easily cleaned. The machine operates to work itself clean, leaving but little, if any, residue within the several spaces in the case and combined forcer and cutter.

I claim as my invention—

1. The combination of the case having tapering portion, the combined forcer and cutter fitted thereto, the crank-shaft projecting from the large end of said combined forcer and cutter, the cap E, having a bearing for the said crank-shaft, and the hub 16, fitted to the large end of said case, the case and cap being provided with engaging lugs for holding and forcing the parts together, and the dog 21 for locking said cap in place, substantially as described, and for the purpose specified.

2. In a meat-cutter, the combination of the case, the holding-cap fitted thereto and having serrations 20 at the edge, the dog 21, and crank-pin or eccentric by which it is secured to the case, substantially as described, and for the purpose specified.

3. The combination of the case provided with perforated portion, and the combined forcer and cutter having the longitudinal cutters and forcing-ribs, the ends of the latter extended into the space between said longitudinal knives, substantially as described, and for the purpose specified.

4. The combination of the combined forcer and cutter with the case having a series of perforations, the feeding-ribs 13, and a circumferential cutter or cutters, substantially as described, and for the purpose specified.

5. The combination of a combined forcer and cutter with the case having a series of feeding-ribs and perforations, and the shearing longitudinal cutter 11 on the forward side of said perforations, substantially as described, and for the purpose specified.

6. The combination of a case having feeding-ribs and cutters, the combined forcer and cutter having forcing-ribs and longitudinal cutters, and a longitudinal space immediately in front of each cutter, to which the respective forcing-ribs lead, substantially as described, and for the purpose specified.

OLIVER D. WOODRUFF.
